Washington Tampa Bollard, Spring City Electrical Mfg. Co.,
Jan. 1990.

Architectural Area Lighting, Concrete Bollards, 1994.

Primary Examiner—Lisa Lichtenstein

(74) Attorney, Agent, or Firm: Lyon & Lyon LLP

(57) CLAIM

The ornamental design for a round concrete bollard luminaire, as shown and described.

DESCRIPTION

FIG. 1 is a side elevation view of a round concrete bollard luminaire, showing my new design, the other three sides being identical to that shown,

FIG. 2 is a top view; and,

FIG. 3 is a perspective view.

The bottom (not shown) of the luminaire does not constitute an integral part of the disclosed and claimed design.
